UNITED STATES PATENT OFFICE.

JAMES G. LAMB, OF CHATTANOOGA, TENNESSEE.

DRAFT-PRODUCER FOR STOVES.

1,297,871.

Specification of Letters Patent. Patented Mar. 18, 1919.

Application filed March 30, 1918. Serial No. 225,731.

To all whom it may concern:

Be it known that I, JAMES G. LAMB, a citizen of the United States, residing at Chattanooga, in the county of Hamilton and State of Tennessee, have invented new and useful Improvements in Draft-Producers for Stoves, of which the following is a specification.

This invention relates to stove attachments, particularly to draft producing devices, and has for its object the provision of a device adapted to be associated with a stove pipe at or near its point of connection with a stove and embodying a rotary fan whereby suction may be produced within the pipe for causing a proper draft upon the fire.

An important object is the provision of a device of this character so constructed that when in place it will not interfere with the ordinary draft and which is divided into compartments one of which has associated therewith a movable deflecting plate or valve which may be shifted whereby one compartment may perform the functions of an inlet and the other the functions of an outlet.

Another object is the provision of a device of this character embodying a fan and provided with means whereby the fan may be prevented from rotation in the wrong direction.

A further object is the provision of a device of this character which will be extremely simple and inexpensive in manufacture, efficient in service, durable in use and a general improvement of the art.

With these and other objects and advantages in view the invention consists in the novel construction and arrangement of parts to be hereinafter more fully described and illustrated in the accompanying drawings in which:

Figure 1 is a front elevation of the device.

Fig. 2 is an elevation of the opposite side.

Fig. 3 is a horizontal sectional view on the line 3—3 of Fig. 1.

Fig. 4 is a cross sectional view on the line 4—4 of Fig. 3.

Fig. 5 is a longitudinal sectional view on the line 5—5 of Fig. 3 showing the deflecting plate or valve in its open position and

Fig. 6 is a view similar to Fig. 5 showing the plate or valve in its closed position.

Referring more particularly to the drawing the numeral 5 designates the casing as a whole which includes the front and back walls 6 and 7, the end wall 8 and the top

and bottom walls 9 and 10 respectively which are connected at one end by a curved portion 11. Adjacent one end of the casing the top and bottom walls are provided with holes 12 and 13 surrounded by flanges 14 whereby the device may be inserted between the ends of stove pipe sections or inserted between the top of the stove and the stove pipe. The casing 5 is divided by a partition 15 which, together with the wall 6 and adjacent portions of the end walls 8 and 11 and also the top and bottom walls, defines a compartment 17. The space between the partition 15 and the side wall 7, top and bottom walls and end walls, is divided by a transverse plate 18 into two chambers 16 and 19, the former of which is in position to communicate with the openings 12 and 13 in the top and bottom plates and the latter of which constitutes a fan chamber. The partition 15 has formed therein a relatively large opening 20 establishing communication between the compartment 17 and the fan chamber 19. The transverse plate 18 terminates short of the bottom wall 10 so that communication may be established, when desired, between the chambers 16 and 19.

A shaft 21 is journaled through the sides of the casing 5 and extends substantially centrally of the fan chamber 19 and has secured thereon within the chamber 19 a plurality of blades 22 forming a fan. At the front side 6 of the casing the shaft 21 has suitably secured thereon a pinion 23 which meshes with a gear 24 revoluble upon a stub shaft 25 secured to the front wall 6. The gear 24 is provided with an operating handle 26 whereby it may be rotated for eventually rotating the fan as will be obvious. In order that the fan may not be rotated in the wrong direction, I provide upon the end of the shaft 21 at the rear wall 7 a ratchet 27 engaged by a spring pressed pawl 28.

Disposed within the compartment 16 and pivoted transversely thereof as shown at 29 is a plate 30 movable between a vertical position as shown in Fig. 5 and a horizontal position as shown in Fig. 6 and adapted to close the portion of the hole 13 lying within the compartment 16. In order that the plate 30 may be moved from one position to another, I provide a handle 31 in the nature of a wire pivotally connected as at 32 with the plate 30 and extending through a hole

33 in the top wall 9 adjacent the hole 12 therein. At its outer end the wire handle 31 is looped to provide a finger engaging portion 34 and adjacent its pivoted end is provided with an offset portion 35 engaging the hole 33 for holding the plate 30 in a vertical position as clearly shown in Fig. 5.

The operation of the device is as follows: When the plate 30 is in its raised position 10 and extends vertically as shown in Fig. 5, the smoke pipe is entirely unobstructed and the draft is normal. If however the fire smokes and does not burn properly, in order to create an efficient draft, it is merely necessary to disengage the offset portion 35 of the wire handle 31 from the hole 33 and allow the plate 30 to descend to its horizontal position closing one half of the hole 13. The smoke and other products of combustion will then pass upwardly through the portion of the hole 13 within the compartment 17 and will pass on in the usual manner. The operator then grasps the handle 26 and rotates the gears 24 and 23 25 whereupon the fan will be set in motion and the smoke will be drawn from the compartment 17 through the opening 20 into the fan chamber 19 and will be forced out under the transverse plate 18 into the compartment 16 whence it will be discharged into the portion of the stove pipe extending above the casing. The degree of forced draft thus caused is regulated entirely by the speed at which the gear 24 is rotated. When the device has been operated for a length of time 30 sufficient to cause the fire to burn satisfactorily, the plate 30 is raised to its vertical position, whereupon the normal draft will be resumed.

40 From the foregoing description and a study of the drawings it will be apparent that I have thus provided a device suitable for attachment at or near the junction of a stove pipe with a stove whereby any desired degree of draft may be produced quickly and simply.

It will of course be understood that I reserve the right to make such changes in the form, construction and arrangement of 50 parts as will not depart from the spirit of my invention nor the scope of the subjoined claims.

Having thus described my invention I claim:—

55 1. A device of the character described, comprising a casing provided in its top and bottom walls with openings surrounded by flanges adapted for engagement within the adjacent ends of spaced stove pipe sections, 60 a vertical longitudinal partition plate dividing said casing into two compartments, said partition plate extending across the centers of said openings, a vertical transverse plate extending from one side of said casing to 65 said partition and subdividing one of said

compartments into a fan chamber and a chamber arranged between said openings, said partition being provided with an opening establishing communication between the fan chamber and the other of said compartments, said plate being spaced from the bottom wall to provide an opening establishing communication between said fan chamber and said last named chamber, a fan journaled within said fan chamber, means 70 for rotating said fan, and a plate pivoted beneath said transverse plate at the bottom wall of the casing and movable selectively to seat upon the bottom wall for closing communication through the associated half of 80 the lowermost of said first named openings and said last named chamber or to seat upon said transverse plate for closing communication between said fan chamber and said last named chamber. 85

2. A device of the character described comprising a casing provided in its top and bottom walls with openings surrounded by flanges adapted for engagement within the adjacent ends of spaced stove pipe sections, a vertical longitudinal partition plate dividing said casing into two compartments, 90 said partition plate extending across the centers of said openings, a vertical transverse plate extending from one side of said casing to said partition and subdividing one of said compartments into a fan chamber and a chamber arranged between said openings, said partition being provided with an opening establishing communication 95 between the fan chamber and the other of said compartments, said transverse plate being spaced from the bottom wall to provide an opening establishing communication between said fan chamber and said last named chamber, a fan journaled within 100 said fan chamber, means for rotating said fan, and means for selectively cutting off communication between said fan chamber and said last named chamber or between the 105 last named chamber and the associated half of the lowermost one of said first named openings.

3. A device of the character described comprising a casing provided in its top and bottom walls with openings surrounded by flanges adapted for engagement within the adjacent ends of spaced stove pipe sections, 115 a vertical longitudinal partition plate within said casing, said partition plate extending across said openings, a vertical transverse plate extending from one side of said casing to said partition and defining therewith and with the adjacent walls a fan chamber and a chamber arranged between said openings, 120 said partition being provided with an opening leading into said fan chamber, said transverse plate being spaced from the bottom wall to provide an opening establishing communication between said fan chamber 125 and the associated half of the lowermost one of said first named openings.

and said last named chamber, a fan journaled within said fan chamber, means for rotating said fan, and means for selectively cutting off communication between said fan chamber and said last named chamber or between the last named chamber and the associated half of the lowermost one of said first named openings comprising a plate pivoted below said transverse plate at the bottom of the casing and swingable in a vertical plane, and an angular handle member secured to the free edge of said pivoted plate and extending through a hole in the top of the casing.

In testimony whereof I affix my signature. 15

JAMES G. LAMB.
